UNITED STATES PATENT OFFICE.

HENRY SYMONS, OF TOTNES, COUNTY OF DEVON, ENGLAND.

GAS-CARBURETOR.

SPECIFICATION forming part of Letters Patent No. 317,686, dated May 12, 1885.

Application filed June 13, 1884. (No model.) Patented in England June 4, 1883, No. 2,767, and in France July 23, 1883, No. 156,693.

To all whom it may concern:

Be it known that I, HENRY SYMONS, a subject of the Crown of Great Britain, residing at Totnes, in the county of Devon, England, have invented a new and useful Improvement 5 in Gas-Carburetors, of which the following is a specification, reference being had to the accompanying drawings.

The object of this invention is to provide an 10 efficient apparatus which may be used by consumers of gas for the purpose of enriching the gas supplied to them by the gas-companies.

Figure 1 in the drawings is a central vertical sectional view of a carburetor constructed 15 according to my invention. Fig. 2 is a vertical sectional view, on a larger scale, of a valve used in the carburetor and of the box for said valve and the passage which it controls.

B designates a cylindrical or other shaped 20 vessel or casing, having at the bottom an inlet-nozzle, e, which is to be connected with the service-pipe or with a pipe from the meter.

j is a closed annular reservoir, placed or provided inside the casing B, to contain the oil or 25 carbureting liquid, and having a central well, j', formed within its sides. The connection between the reservoir j and the well j' is made by means of the pipe j², in which a valve, j³, is placed. This valve may be of any suitable 30 form, but that shown in the detached view, Fig. 2, is simple and answers well the purpose. The valve-stem is attached to a float, j⁴, which floats in the liquid in the well j' by its buoyancy, assisted by the spring j⁵, and will, so 35 long as there is a sufficient quantity of liquid in the well j', maintain the valve closed. The opening of this valve will be effected by means hereinafter described.

Fitted to the inlet nozzle e is a tube, k, projecting upward into a second tube, k', which rests on the carburetor B, and is closed at top in any convenient manner. This tube k' is provided in its sides with vertical slits, which extend from a little above the level of the top 45 of the reservoir j to the bottom of the tube, to permit of the gas passing in contact with the carbureting-liquid. Round the tube k' is fitted a cone, l, which rests on a perforated galley, m, secured about half-way up, to the walls of 50 the cylinder B.

Below the cone l is secured to the tube k' by a flexible connection, b, a wooden or other

float, n, which is intended to float in the liquid in the well j.

Suitable openings, o, which may be covered 55 with a light fringe, if desired, are left about the float for the gas to pass out. The space between the perforated galley m and the top of the cylinder is filled with silicate cotton or cotton-wool, a mixture of charcoal and fibrous 60 material, or any other suitable absorbent material.

The annular reservoir j is filled by means of the tube p, a smaller tube, p', being provided to allow for the escape of air during refilling, 65 and also to serve as a guide for the gage-rod p², to which the float p³ is connected. When the cap p⁴ is removed, this float will rise to the top of the oil in the reservoir, and the gage rod p², being divided off or graduated, will 70 indicate the quantity of liquid in the reservoir.

The cylinder is closed by a cover, q, which may be screwed down to the top, so that it may be readily removed when it is desired to clean out the carburetor. Below the cover q 75 a perforated funnel-shaped piece, q', is placed to prevent the silicate cotton, cotton-wool, or other solid material entering or stopping up the outlet t, provided in the cover for the egress of the carbureted gas. 80

The quantity of liquid contained in the well is just sufficient to keep the float n floating, and as evaporation takes place this float descends and rests on the valve-float, and by its weight opens the valve j³, thus allowing a 85 sufficient quantity of liquid to enter the well to again cause it to float. This operation is being continually repeated, and thus a fresh supply of liquid is always entering the well. 90

It has been found, that, where a large surface of carbureting-liquid is exposed, the higher hydrocarbons pass off very rapidly, and the gas for a time is thereby enriched to a greater extent than is necessary, the enrichment of the gas decreasing in proportion as 95 the evaporation of the lighter particles takes place; but by the means just described I obtain a regular and continuous supply of the lighter hydrocarbon vapors, which has a corresponding effect on the enriching of the gas. 100 The gas passes up the tube k and down outside the same, and then passes through the slits in the tube k' and the openings o in the float, and takes up the vapor from the liquid

before it passes through the silicate cotton or cotton-wool or other material to the outlet *t*.

Provision should be made for the entrance of gas or vapor into the reservoir, to prevent the formation of a vacuum when drawing off the oil.

The primary object of the silicate cotton or cotton-wool or other material is to deprive the gas of any excess of hydrocarbon it may have taken up, but after a time the silicate cotton or cotton-wool will become more or less charged with liquid, and it will then also serve to supply any deficiency of carbureting-liquid to the gas, if required. Any excess of oil will drain off from the cotton-wool, silicate cotton, or other material and run back.

Having now described my invention and explained the manner of carrying the same into effect, I claim—

1. The carbureting apparatus consisting of a cylindrical or other shaped vessel containing a closed annular reservoir, *j*, for oil or

carbureting-liquid, well *j'*, connecting-pipe *j²*, valve arrangement *j³ j⁴ j⁵*, tubes *k k'*, cone *l*, galley *m*, flexibly-connected float *n*, filling-pipe *p*, cover *q*, and perforated piece *q'*, all arranged substantially as herein shown and described. 25

2. In a gas-carbureting apparatus, the combination of the closed annular reservoir *j*, well *j'*, valve-connection *j² j³ j⁴ j⁵*, filling-pipe *p*, air-pipe *p'*, gage-rod *p²*, float *p³*, and cap *p⁴*, all substantially as herein shown and described. 30

3. In a gas-carbureting apparatus, the combination of the reservoir *j*, the well *j'*, the stationary pipes *k k'*, flexibly-connected float *n*, 35 and valve-float *j⁴*, substantially as and for the purpose set forth.

HENRY SYMONS.
